UNITED STATES PATENT OFFICE.

WILLIAM E. WREAD, OF LOS ANGELES, CALIFORNIA, ASSIGNOR, BY MESNE ASSIGNMENTS, TO MCKINNEY MANUFACTURING COMPANY, OF PITTSBURGH, PENNSYLVANIA, A CORPORATION OF PENNSYLVANIA.

NIGHT-LATCH UNIT.

Application filed September 4, 1926. Serial No. 133,632.

This invention includes a novel arrangement of parts whereby to secure a closure against being opened by burglars.

This invention relates to that class of locks having no knob on the outer side of the door and operated by a knob on the inner side of the door, and made burglar proof by a paracentric key and keyhole in the ward barrel, the keyhole of which is open to the outside of the door.

An object is to make a night latch adapted to be installed in the door instead of on the surface of the door thus to give a more dressy appearance than is possible with night latches heretofore in common use.

Some of the advantages gained are that the striking plate is seated in the jamb and is concealed by the closed door and cannot be removed or tampered with when the door is closed and said striking plate does not mar the casing.

An object is to provide a night latch installation in which the outside finish may be varied at small expense so as to match with any form of hardware finish that is placed on the remainder of the building with which the night latch is provided, and so that the exposed parts may be of polished brass, or other fine material and of any design, expensive or otherwise.

An object is to provide an inexpensive and superior latch lock that is interchangeable with any type of knob either large or small, and that can be used in compact installation with a non-lockable latch, making it a cheap form of a single fixture comprising both a non-lockable latch and a night latch.

Another object is to provide means whereby the installed night latch will be immovably fixed to the closure in which it is installed, and to provide for convenient and accurate adjustment of the night latch mechanism with reference to the sides of the closure and the center of the opening through which the bolt operates.

A further object is to produce a night latch of the character above stated which can be made almost exclusively of stampings and die castings.

An object is to provide a simple and convenient means whereby the latch bolt may be locked in extended position and also may be locked in retracted position.

An object of the invention is to make pro-

vision whereby equal partial revolution of the bolt retracting element in either direction will move the bolt to the same extent.

In order to accomplish this object, I have located the ward barrel centrally of the cylinder.

By this arrangement it is easier for the householder to center the key in the keyhole in the dark.

Cheapness of manufacture, ease of assembly and ease and cheapness of installation are further objects of this invention.

Other objects, advantages and features of invention may appear from the accompanying drawings, the subjoined detailed description and the appended claims.

The accompanying drawing illustrates the invention.

Figure 1 is a broken perspective view partly in section showing a night latch unit with cylinder lock in place in a closure, a fragment of which is shown.

Fig. 2 is a fragmental view of the inside ends of the lock cylinder and ward barrel and its washer, and the inner faces of the front finish.

Fig. 3 is a view of the inner face of the cam disk removed from the cylinder.

Fig. 4 is an edge view of the disk shown in Fig. 3.

Fig. 5 is a fragmental elevation together with fragments of the closure and door jamb and striking plate in section.

Fig. 6 is a plan view partly in section on line x^6 , Fig. 5.

Fig. 7 is a perspective view of the inner side of an anchor plate detached.

The main cylinder 1 corresponds practically to well known main cylinders of cylinder locks; the same having a threaded portion 2 which is screwed into the housing 3 and thereby fastened in place.

The ward cylinder 4 is journalled in the main cylinder and is operatively connected by any suitable means with a disk 5 provided with tappet operating pins 6 arranged near the perimeter of the disk 5.

7 is a tappet inside the housing and provided on one of its sides with a bolt connection 8, which is fixed thereto, and is held non-revolvable thereby and extends through a guide 9 in the housing.

The bolt connection 8 is normally projected into latching position by a spring 10 act-

ing on the tappet 7. Said housing, tappet, spring and bolt connection correspond to those described and claimed in my application for bolt operating mechanism for locks and latches, Serial No. 133,628, filed on the 5 4th day of September, 1926.

The bolt connection 8 is provided on one side with a notch 11 to engage a revolvable locking pin 12 that is mounted in a pin-way 10 13, and said pin is notched at 14 on one side to accommodate the cylindrical portion of the bolt connection 8, so that when the pin is turned with its notch toward the bolt connection, said connection is free to be operated 15 by the spring and tappet.

The web 15 of the pin at the notch 14 is arranged to intercept the bolt connection 8 by fitting into the notch 11, therein, when said connection is in its projected or locking position; and the said web 15 intercepts the end 20 of the bolt connection 8 when the bolt is retracted.

By this arrangement the bolt may be locked either in the retracted or in the locking position by simply turning the pin 12, when the bolt is in position for such locking. By this means the bolt becomes a dead bolt when the pin is turned to cause the web to engage in the notch 11; and the bolt cannot be operated 25 30 by the tappet from either side either with a key or by a knob when thus locked by the pin web.

The tappet 7 is also operated by an arcuate lug 16 having rounded ends and mounted on a disk 18 that is fixed to a hub 17 of the knob 35 spindle 19 to which the knob 20 on the inner side of the door is attached. The housing 3 is provided with a threaded hub 21 adapted to extend outside of the door closure 22 when 40 the lock is in place in the hole 23 bored through the closure from side to side to receive the lock.

The finish plate 24 on the outside of the lock surrounds the threaded cylinder 1, and 45 is provided with a cylindrical flange 25 to hold the web of the finish plate away from the closure to accommodate an anchor plate hereinafter described.

The outer end of the lock cylinder has a 50 head 26 of less diameter than the threaded portion 2 of such cylinder; and said cylinder has a notch 28 between its head 26 and its threaded portion 2. 29 is a finishing cap fitted over the head and having its inner rim inserted into and hooked in the notch by pressing or spinning. The notch is preferably annular, extending entirely around the barrel; and the annular hook or retainer 30 is preferably the inturned edge of the cylindrical cap walls so that the cap is immovably 55 fixed to the cylinder and closes the threads of the threaded portion thereof.

32 is an internally threaded finishing collar screwed onto the cylinder from the inner

end thereof and tight against the finishing 65 cap.

The collar is internally threaded at its inner end and the outer end is reamed out to seat the cap so that the outer face of the cap may be disposed flush with the outer end of 70 the collar when the collar is fully screwed out; that is to say, the reamed out chamber is practically equal in depth to the depth of the cap.

The annular finish plate 24 encircles the 75 cylinder and has its outer face engaged by the inner end of the collar; and the flange of the finish plate fits upon the side of the closure 22.

The finish cap has a central orifice 33 and so the ward barrel is provided at its outer end with a slight flange 34 in the usual manner journalled in the orifice, and the inner end of said barrel is provided with means, as the two studs 35 to extend through holes 35' in 85 the stop washer 36 fitting in a cavity 37 in the inner end of the cylinder; and the washer 36 is secured to the end of the ward barrel by the studs 35 extending through the washer and riveted so that the washer prevents the 90 barrel from coming out of the cylinder.

The barrel is provided with two holes 38 and the tumbler disk 5 is provided with two pins 40 extending into said holes, and the end 95 of the lock cylinder is chambered at 41 to receive the disk.

The pins 6 are preferably cylindrical and are adapted and arranged to act upon the tappet.

44 is an anchor plate consisting of a flat annulus 45 to fit upon the outer face of the closure, and a collar 46 to fit in the hole 23 bored through the closure to receive the lock.

The annulus 45 is provided with an inner notch 48 on one side, which cuts away the collar at that place and said annulus is provided with holes 49 to receive screws 50 that secure the annulus of the anchor plate to the door.

The parts just described are assembled on the door after the anchor plate has been secured thereto. The anchor plate is secured to the door with its notch on that side toward which the bolt 51 will be extended, and the closure is provided with a bolt hole 52 through which the bolt extends.

In installing the lock, the assembled parts are brought to the outer side of the door closure and the housing with its normal contents viz, the spring, the tappet and the parts operated thereby are then inserted through 120 the anchor plate and in order to do this, it is necessary to push in the bolt connection so that it will pass through the anchor plate and into the transverse hole 23.

Then the inside anchor plate 53 is slipped 125 over the housing, and its collar 54 is inserted into the transverse hole and the anchor plate is then secured to the closure by means of the

screws 55. Then the inside finish plate 56 is applied in position against the closure; then the shank of the bolt 51 is inserted through the bolt hole 52 and is screwed into the bolt connection.

Then the guide 57 is placed over the bolt and turned to bring the bolt into proper position to slidingly engage the striking plate 58 when the closure is being shut, and is then 10 driven into the edge of the closure.

Then the inside finish plate 56 is brought into position with its pin handle 59 over the inside end of the lock pin, and the knob nut 60 is then screwed onto the hub of the housing. At this time the workman will relatively 15 adjust the ring collar on one side and the knob nut on the other side by screwing them relatively to each other to bring the bolt connection into position to properly align the bolt 20 with its guide so that it will work freely and true, and will also bring to bear the two finish plates and bind them firmly against the door.

Then the knob 20 will be screwed home positively on the threaded knob spindle, and secured by set screw 61.

I claim:—

1. In a lock adapted to be applied to a closure that has a lock chambering hole extending from side to side, of the closure and a bolt-accommodating hole, extending from the lock chambering hole to the edge of the closure; a cylinder lock; a cap fixed to the end of the lock cylinder; a ring screwed onto the lock cylinder and against the cap; a face plate 30 on the cylinder against the ring; an anchor plate comprising a flange to fit on the face of the closure and a collar adapted to be inserted into the lock chambering hole; a lock housing having one end open and adapted to be 35 screwed onto the barrel and having its other end formed with an externally screw threaded hub; a spring projected bolt connection adapted to be accommodated in the bolt hole; an anchor plate having a flange and a collar 40 corresponding to the first mentioned anchor plate, the collar fitting upon the housing and said flange fitting upon the face of the closure; screws attaching the anchor plates to the closure; a finish plate around the hub and fitted 45 against the closure; and a nut screwed onto the hub and holding the finish plate in place.

2. In a lock cylinder having an externally threaded portion and a reduced cylindrical outer terminal of less diameter than said 50 threaded portion and provided with a groove between said reduced outer end and the externally threaded portion; an annular cap on the end of the cylinder the inner end of the cap being caught in said groove; a ring 55 screwed onto the barrel and against the inner end of the cap; a finish plate on the barrel; an anchor plate surrounding the barrel and adapted to be fixed to a door and adapted to be covered by the finish plate; a housing 60 screwed onto the barrel and adapted to be in-

serted into a lock chambering hole in a door; and means adapted to be connected to the inner end of the housing and to be adjusted thereon and against the door, to center the housing relative to the sides of the door.

3. The combination with a housing; of a lock barrel screwed into one end of the housing; means of greater diameter than the barrel fixed to said housing and adapted to engage a door having a hole adapted to chamber the housing; means adapted to be mounted on the other end of the housing and to engage the face of such door surrounding the chamber; and means screwed onto the housing and adapted to move the housing relative to the inside door engaging means, to clamp the door and locate the housing between the outside and inside face engaging means, and to hold the housing in fixed position relative to said door.

4. In a latch lock unit, a housing having a longitudinal pin bearing and a bolt connection guideway intersecting each other; a bolt connection slidable in said guideway and provided with a notch to receive the pin, and a shoulder to be engaged by the pin; a pin mounted in the bearing and provided with a notch and a web, the notch being adapted to accommodate the bolt connection when the pin is turned in one position and the web being adapted to enter the notch when the pin is turned in another position to prevent the bolt connection from being operated to prevent retraction of the bolt, and said web being adapted to intercept the shoulder of the bolt connection when the bolt is retracted and the pin turned to shoulder engaging position for the purpose of preventing extension of the bolt.

5. The combination with a housing having an externally threaded hub at one end and provided with an internal bearing, said housing being provided at the other end with a threaded seat; an anchor plate on said housing around said seat; a lock cylinder screwed into said seat; a finish plate on said barrel to engage one side of a door; a cap fixed to the outer end of the barrel; a ring screwed onto the barrel and against the cap; a finish plate surrounding the threaded hub to engage the other side of the door; and a nut screwed onto said threaded hub and against the finish plate for the purpose of adjusting the housing between the sides of the door in which the housing is mounted and against the sides of which the finish plates are adapted to engage.

6. In a door fixture of the class described, the combination of a housing adapted to be fitted to a transversely disposed aperture in a door, a bolt member carried by said housing adapted to traverse a bolt passage in a door, exteriorly operable bolt-actuating means in said housing, an anchor plate engaging said housing at opposite ends to align and center said housing and its associated parts, a finishing and door-clamping plate adjustably

connected at one end of said housing, and a finishing and door-clamping plate adjustably connected to the other end of said housing.

7. In a door fixture of the class described, 5 the combination of a housing adapted to be fitted to a transversely disposed aperture in a door, a bolt member carried by said housing adapted to traverse a bolt passage in a door, exteriorly operable bolt-actuating means in 10 said housing, an anchor plate at each end of said housing adapted to engage a door and having an engaging flange to align and center said housing and its associated parts, a finishing and door-clamping plate adjustably 15 connected at one end of said housing, and a finishing and door-clamping plate adjustably connected to the other end of said housing.

8. In a door fixture of the class described, the combination of a housing adapted to be 20 fitted to a transversely disposed aperture in a door, a bolt member carried by said housing adapted to traverse a bolt passage in a door, exteriorly operable bolt-actuating means in 25 said housing, an anchor plate at each end of said housing adapted to engage a door and having a flange provided at one point in its periphery with a clearance notch to center said housing and its associated parts, a finishing and door-clamping plate adjustably 30 connected at one end of said housing, and a finishing and door-clamping plate adjustably connected to the other end of said housing.

9. In a door fixture of the class described, the combination of a housing adapted to be 35 fitted to a transversely disposed aperture in a door, a bolt member carried by said housing and adapted to traverse a bolt passage in a door, bolt-actuating means in said housing, manually operable means secured to one end 40 of said housing to operate said bolt-actuating means, an anchor plate to center said housing at one end thereof, a finishing and door-clamping plate adjustably secured to one end 45 of said housing, key operated means at the other end of said housing to operate said bolt-

actuating means, an anchor plate to center the other end thereof, and a finishing and door-clamping plate adjustably secured to said key operating mechanism.

10. In a door fixture of the class described, 50 the combination of a housing, a bolt member carried by said housing, means in said housing for actuating said bolt member, a knob exteriorly of said housing at one end to operate said bolt-actuating means, a lock cylinder 55 adjustably connected to said housing at the other end and provided with key controlled means to operate said bolt actuating means, anchor plates at each end of said housing to center said housing and its associated parts, and finishing and door-clamping plates adjustably connected with said housing at one end and with said lock cylinder at the other end.

11. A door fixture comprising a latch housing or the like adapted to be fitted into a transversely-disposed aperture of a door, an operating spindle extending from one end of said housing, an anchoring plate having a flange extending inwardly and fitting around 60 said housing, and having another flange portion extending radially for attachment to the side of a door, and a finishing plate surrounding said spindle and secured to the housing in position to overlie the radially-extending 70 flange of said anchoring plate.

12. A door fixture comprising a cylindrical latch housing adapted to be fitted into a transversely-disposed aperture in a door, an anchoring plate having an inwardly-extending 80 flange fitting around said housing and having a radially-extending flange for attachment to the side of the door, and means for holding said anchoring plate and the housing in assembled relation.

In testimony whereof, I have hereunto set my hand at Los Angeles, California, this 20th day of August, 1926.

WILLIAM E. WREAD.
